Filed July 5, 1956, Ser. No. 595,903

9 Claims. (Cl. 242—56)

This invention relates to the continuous winding of web materials.

It is a primary object of the invention to provide a new and improved continuous winder for web materials in which the several operating steps required for the transfer of the web from a fully wound roll to a new core are carried out automatically in proper sequence, and in which particular provision is made for preventing improper sequence of operation.

Another object of the invention is to provide such a winder in which the successive operations of the several parts of the apparatus during roll changing establishes that such operations will be in the proper sequence and also prevents operation of the apparatus in an improper sequence either as the result of an accident or even if the operator should by mistake attempt such improper operation.

It is also an object of the invention to provide auxiliary equipment for combination with an existing non-automatic winder which will convert such winder to automatic operation in the transferring of the web from a fully wound roll to a new core.

Additional objects and advantages of the invention will be apparent from the following description, the accompanying drawings and the appended claims.

In the drawings—

Fig. 1 is a somewhat diagrammatic and partly broken side view of a continuous winder constructed in accordance with the invention and looking toward the drive side thereof;

Fig. 2 is a similarly diagrammatic top view of the winder of Fig. 1;

Fig. 3 is a front view looking from right to left in Fig. 1 and illustrating auxiliary equipment in accordance with the invention of the type employed in Fig. 1 to establish automatic operation of the winder;

Fig. 4 is a detail side view looking from left to right in Fig. 3;

Fig. 5 is a view similar to Fig. 4 looking from right to left in Fig. 3;

Fig. 6 is an enlarged fragmentary view taken as indicated by the line 6—6 of Fig. 7 and showing certain of the controls for the winder;

Fig. 7 is a fragmentary view looking from right to left in Fig. 6;

Fig. 8 is an enlarged fragmentary view showing another of the controls, this view looking from left to right in Fig. 9 and being taken approximately on the line 8—8 of Fig. 9;

Fig. 9 is a view looking from right to left in Fig. 8;

Figs. 10 and 11 are additional fragmentary views illustrating further controls, these views being taken as indicated by the lines 10—10 and 11—11 respectively of Fig. 12;

Fig. 12 is an enlarged elevational view looking from left to right in Fig. 10 and from right to left in Fig. 11;

Fig. 13 is an air circuit diagram; and

2

Fig. 14 is a wiring diagram.

Referring to the drawings, which illustrate preferred embodiments of the invention, the end stands 20 and 21 in Figs. 1 and 2 from the base frame for a double armed reel comprising arms 22 and 23 on a shaft 24 connected with an indexing drive motor 25 for effecting controlled rotation of the reel, the motor 25 being shown as of the gearhead type connected with shaft 24 by a belt or chain drive 26. The reel is provided with a pair of core spindles 30 and 31 each adapted to carry a core 32 on which a roll 33 is to be wound. Indexing of the reel controls the path of the web 35 to successive cores 32 from suitable tension control means, shown as a pair of pull rolls 36, for delivering the web to the winder at a predetermined controlled speed, which is readily determined by the speed of the machine from which the web is supplied to the winder.

Each of these spindles 30 and 31 is provided with its individually controlled friction clutch 40 and 41 respectively carried by an additional reel arm 42, and the driving members of both clutches are connected by chain drives 43 with a sleeve 44 free of shaft 24. This sleeve 44 is driven through a chain or belt drive 45 by a constant horsepower source for continuously driving sleeve 44 at a rate decreasing in response to increasing torque, and which is represented in Fig. 2 by a motor 46. In operation, this drive is correlated by conventional electric control means with the speed of the web to maintain substantially constant tension in the web by driving successive winding rolls at an angular speed which decreases at a proper constant rate to maintain an effectively constant peripheral speed for the roll.

The winder as described up to this point requires manual control during roll changing, a suitable system for such control being shown in my copending application Serial No. 513,369, filed June 6, 1955 and issued as Patent No. 2,828,926 on April 1, 1958 to the same assignee as this application. The present invention provides auxiliary equipment designed for combination with such non-automatic winder which will convert the winder to automatic operation accompanied by adequate assurance for a proper automatic sequence of operation during roll changing together with maximum assurance against improper operation once the roll changing sequence has been initiated.

Referring particularly to Figs. 3—5, the auxiliary unit includes a double end stand 50 at the drive side of the winder and a single end stand 51 at the control side. The end stand 50 carries an idler pulley 52 and a drive pulley 53 cooperating with a second idler 54 to support the auxiliary drive, represented by a belt 55, which is utilized to accelerate the successive spindles to proper speed before and during roll change. The idler 54 is carried by a bracket 56 which may be a part of the stand 50 or separately mounted on the floor as shown. The drive pulley 53 is carried by shaft 57 mounted in the end stand 50 and driven by a drive motor 58 through a belt or chain drive 59.

The auxiliary drive is adapted to be selectively connected with the spindles 30 and 31, and this is illustrated by means for bringing the belt 55 selectively into driving engagement with one or the other of the pulleys 60 and 61 mounted on the spindles 30 and 31 respectively between the reel arms 22 and 42 to provide a selective direct drive to either spindle independently of the main power source 46. This means includes tensioning means for belt 55 comprising a pulley 62 mounted by means of arms 63 on a pivot 64 in end stand 50. The arms 63 are in turn connected by a lever 65 with the piston rod of an air cylinder 66 mounted on the stand 50 and operable to move the pulley 62 into and out of tensioning relation

with the belt 55. The end stands 50 and 51 are reversed in Figs. 1 and 2 from the arrangement in Fig. 3, but this merely exchanges the drive side and control side of the unit and does not otherwise affect it.

The end stands 50 and 51 cooperate to support a knife assembly for severing the web at the properly timed instant during roll changing. The knife blade 70 is carried by a plurality of arms 71 secured to a rock shaft 73 which is in turn carried by a pair of arms 74 and 75 secured to a torque tube 77 free on a shaft 80 extending between the stands 50 and 51. An arm 81 extending from tube 77 is connected to the piston rod of an air cylinder 82 carried by a bracket 83 secured in fixed relation with the end stands as by mounting on the floor, and the arrangement is such that when pressure is applied to the lower end of the cylinder, the tube 77 will rock to move the arms 74 and 75 as shown in Figs. 5 and 10 from their dotted line positions to the full line positions.

The cutting movement of the knife with respect to the arms 74 and 75 is effected by a separate control. A sprocket 85 on the shaft 73 is connected by a chain 86 to a sprocket 87 on the hub of an arm 88 free on shaft 80. The arm 88 is in turn connected to the piston rod of an air cylinder 89 secured to bracket 83, and Fig. 5 shows how the application of pressure to the upper end of cylinder 89 will cause the knife arms 71 to swing in clockwise direction for cutting movement of the knife.

The end stands 50 and 51 also carry a pressure roll 90 which forms a pressure nip with the winding roll through which the web travels and also operates during roll changing to grip the web against the new core and thus cooperates with the knife to complete the desired flying start on the new core. The pressure roll 90 is carried by a pair of arms 91 and 92 pivoted on the shaft 80 and each including extensions 93 which are connected with the piston rods of a pair of air cylinders 95 secured at their lower ends to the bracket 83 and a similar bracket 96 or a portion of the end stand 51. The pressure supply to the cylinders 95 is normally maintained throughout the winding operation rather than selectively during roll changing, as indicated in the air circuit diagram in Fig. 13 by the manual control valve 99, which is connected with the main air supply line 100 by an adjustable reducing valve 101 together with a pressure gauge 102.

The control arrangements for the other air-operated parts are also illustrated in Fig. 13. Thus the tensioning cylinder 66 for the belt 55 is controlled by a solenoid valve SV-1 which is energized in timed relation with the operations of the other parts of the winder during roll changing as described hereafter in connection with the wiring diagram. Similarly the knife pivot cylinder 82 and the knife operating cylinder 89 are controlled by solenoid valves SV-2 and SV-3. The clutches 40 and 41 on the winder spindles are also arranged for individual engagement and disengagement by means of solenoid valves SV-4 and SV-5 respectively, and the pressure line to each of these clutches is also connected with one of a pair of pressure switches PSA and PSB connected in series as shown in Fig. 14 and arranged to be opened when pressure is applied to engage the associated clutch. Each of the solenoid valves is also shown in Fig. 13 as provided with a reducing valve 101 and pressure gauge 102.

The sequence of operation of the winder during roll changing is controlled primarily by a series of limit switches which are shown in detail in Figs. 6-11. Referring to Figs. 6 and 7, three of these switches LS-1, LSA and LSB are mounted on the end stand 16 and operated by cams 105, 106 and 107 on the winder shaft 24, the cam 105 having a pair of opposed high points while the cams 106 and 107 have single high points since the roll change occurs twice for each complete revolution of the arms 22 and 23. Normally closed switch LS-1 is of the single-pole double-throw variety, while switches LSA and LSB are normally open single-pole switches. Figs. 8 and 9 show switch LS-5, which is a normally

closed switch mounted on the knife pivot arm 75 and adapted to be opened by a cam 108 mounted on the hub of the knife operating arm 88.

Additional limit switches are shown as mounted on a bracket 110 secured to the floor or otherwise in fixed relation with the end stands 50 and 51. Switches LS-3 and LS-4 are mounted on one side of bracket 110 and are operated by cams 111 and 112 carried by the torque tube 77. Both of these switches are normally open and are adapted to be closed in the retracted and advanced positions of the knife pivot arms respectively. Switch LS-2 is a single-pole double-throw switch mounted on the other side of bracket 110 and operated by a cam 113 depending from the hub of the pressure roll arm 92.

The electric controls provided by the invention and the sequence of operation which they establish will be understood from the following description in conjunction with the wiring diagram in Fig. 14, in which the A.C. power lines L-1 and L-2 may be provided with a suitable disconnect switch (not shown). In the normal operation while a roll 33 is being wound, the reel arms will be generally in the reverse of the position shown in Fig. 1 to the extent that the winding roll 33 will be in engagement with the pressure roll 90. The circuits as a whole will be as shown in Fig. 14 with the exception that switch LS-3 will be held closed because the knife pivot arms are retracted, and also one of the clutches 40 or 41 will be engaged by energization of its associated control relay. If it is assumed that clutch 40 is engaged, then the relay CLAR will be energized and locked in through limit switch LS-5 and the normally closed push button switch 120. Since valve SV-4 is energized to engage clutch 40, pressure switch PSA will be open, and relay CLPR will therefore also be open.

The main power source 46 operates during winding at a constantly decreasing speed determined by its control circuits as pointed out above, and since such circuits are largely conventional, they are indicated in Fig. 14 merely by the block diagram 125. Similarly the details of the circuits for the indexing motor 25 are not shown in greater detail than the indication of a reversing switch 122, which is operated selectively by the relays WF and WR to produce forward and reverse indexing movement of the reel arms respectively. Fig. 14 also indicates each of these relays as operating a normally closed switch in the circuit to the other relay in order to prevent both of these relays from being energized at the same time.

In the above example, when the roll 33 is fully wound and it is desired to change to a new core, the roll change sequence is initiated by closing the push button switch 126. This completes an energizing circuit for relay SBR through the normally closed manual switch 130 and the back contacts 131 of relay SMR, and relay SBR locks itself in through its contacts 132. Closing of relay SBR completes an energizing circuit through its contacts 133 to the solenoid valve SV-1 to effect tensioning of the belt 55. Similarly, closing of relay SBR will complete an energizing circuit to the indexing motor relay WF, this circuit running through switch LS-3, which is still held closed, the back contacts of switch LS-1, and the contacts 134 of relay SBR.

This sequence of events causes the indexing motor 25 to move the reel in clockwise direction as viewed in Fig. 6 until the switches LSB and LS-1 have been tripped by their respective cams, which will bring the reel into the roll starting position shown in Fig. 1 wherein the empty core is engaged with the pressure roll 90. In this position, the pulley 61 will be engaged with the belt 55 to bring the new core 33 up to web speed. The reel is stopped in this position by operation of switch LS-1, which cuts off the circuit to relay WF and instead completes a circuit through the contacts 135 of relay SBR to the solenoid valve SV-2.

Energizing of valve SV-2 causes the knife pivot arms

to move into their full line positions shown in Figs. 2 and 5, and the accompanying movement of the cams carried by the torque tube 77 first opens switch LS-3 and then closes switch LS-4 in preparation for operation of cutting and transferring the web to the new core. This operation is completed by depressing the push button switch 140 to energize valve SV-3, which causes the knife to carry out its cutting stroke as shown in Fig. 1 by cutting the web and carrying the cut leading end around the new core towards the nip with the pressure roll 90.

When the knife approaches the limit of its cutting stroke, the cam 108 on the knife-operating arm 88 opens switch LS-5, thus breaking the locking circuit for relay CLAR and causing clutch 40 to deenergize. The valve SV-3 remains energized only so long as switch 140 is held closed, and as soon as this switch is released, the knife returns to its retracted position and permits switch LS-5 to reclose without immediate effect. However, the deenergizing of valve SV-4 removed pressure from switch PSA and thus allowed this switch to close and thereby to complete an energizing circuit for relay CLPR.

Closing of relay CLPR completes a circuit through its contacts to the main power source control circuits 125 signaling the completion of roll 33, severance of web, and transfer of the web to the core driven by belt 55. During the subsequent interval, the main power source represented by the motor 46 now disconnected from the web accelerates to bring its speed up to the r.p.m. necessary to match the speed of the empty core which is being driven by the belt 55. The main power source control circuits include a signal means which is represented by the relay 145, effective to complete the energizing circuit for a relay SMR when this matching speed condition is attained.

When relay SMR closes, it completes an energizing circuit for relay CLBR through its contacts 150 and switch LSB, which has been closed by cam 107, and thereby completes an energizing circuit for valve SV-5 to cause clutch 41 to engage. Closing of relay SMR will also close its contacts 151 in the circuit to relay CLAR, but this circuit will remain open during this roll change because switch LSA remains open until the reel shaft has rotated through 180°. As soon as valve SV-5 is energized, it will also supply pressure to switch PSB, thus opening this switch and causing relay CLPR to deenergize, which in turn operates through its back contacts to restore the control circuits 125 to their normal operation.

Since engagement of clutch 41 connects the winder power source 46 with the spindle 31, the auxiliary drive is removed, and this change is initiated simultaneously with engagement of the clutch by deenergizing relay SBR as a result of the opening of its holding circuit through the back contacts 131 of relay SMR. This deenergizes valve SV-1 to shift the tensioning pulley 62 to its retracted position, and the air flow to clutch 41 and the bleed off of air from cylinder 66 are readily regulated to provide a smooth transition of winding power from the auxiliary drive to the main winder power source. Opening of relay SBR will also deenergize valve SV-2 to cause the knife pivot arms 74 and 75 to return to their retracted position, and the accompanying movement of the cams on torque tube 77 will cause switch LS-4 to open and switch LS-3 to close.

This reestablishes normal winding conditions, which will continue until the layers of the web built up on the core 33 have increased to a thickness causing movement of the pressure roll arms 91 and 92 sufficiently to trip switch LS-2. This completes an energizing circuit to relay WF to produce forward indexing movement of the reel until switch LS-2 is reset, and this incremental build-up will continue so long as the winding roll remains in engagement with the pressure roll 90. Switches LS-1 and LSB will be reset by their operating cams 105 and 107 after the reel has indexed an adequate distance

beyond its roll changing position, and since switch LS-5 has already reclosed, the locking circuit for relay CLBR will remain complete after switch LSB opens. Similarly the relay SMR will deenergize after the thickness of the new roll has increased to such extent that the speed of the main power source has decreased sufficiently from its empty core speed to provide a suitable signal of this changed condition, as by opening the relay 145. This returns the contacts of relay SMR to their normal positions in preparation for the next roll change.

The indexing movements of the reel during the subsequent period of winding on the new roll will remain under the control of switch LS-2 until the next roll change is initiated by operating switch 126. During the winding of this new roll, the full roll will be removed at the back of the winder and replaced by a new core in the usual way.

The invention accordingly provides for accurate automatic control of the movements of the several parts 20 during roll changing, and at the same time it retains for the operator the selection of the time for initiating a roll change and the time for effecting the actual web transfer while still preventing the operator from causing operation of any of the parts in the wrong sequence. 25 Thus as soon as the push button switch 126 has been closed to initiate the roll changing sequence, the several parts will interact with each other in the proper order until everything is in position for the actual web transfer. Thereafter, the only manual act required is the 30 momentary closing of switch 140 to actuate the knife cylinder, and the remaining steps of the roll changing operation will then be carried out automatically. In fact, even if the operator should hold switch 140 closed longer than necessary, this will not interfere with completion of the roll change.

The remaining parts in the wiring diagram which have not as yet been identified provide for manual control of the several steps in the roll changing operation if such should be desired. Thus the switches 160 and 40 161 provide for forward and reverse movement respectively of the indexing of motor 25, and switch 130 provides for manual opening of relay SBR. Similarly manual switches 162 and 163 provide for selective manual energizing of the clutch relays CLAR and CLBR respectively, while switches 126 and 165 provide for manual actuated opening of these clutch relays. Whenever any of these manual controls are used, the same interlocks are effective to prevent improper operation as when the winder is functioning under the automatic control as 45 already described.

While the forms of apparatus herein described constitute preferred embodiments of the invention, it is to be understood that the invention is not limited to these precise forms of apparatus, and that changes may be 50 made therein without departing from the scope of the invention which is defined in the appended claims.

What is claimed is:

1. Continuous winding apparatus for web material comprising a reel for simultaneously supporting a winding roll and a new core, a main drive for selectively driving said roll and core, an indexing drive for said reel to advance said new core to a roll starting position, an auxiliary drive for driving said new core in said starting position at a predetermined rotational speed, 60 means responsive to indexing of said new core to said starting position for causing driving engagement of said core with said auxiliary drive, additional means responsive to indexing of said core to said starting position for stopping said indexing drive, means operable only after operation of said additional responsive means for effecting cutting of said web and transfer of the cut leading end thereof to said core, means responsive to operation of said last named means for disconnecting said winding roll from said main drive, means responsive to operation of said disconnecting means for causing 70 75

acceleration of said main drive to said predetermined rotational speed, means for sensing that the speed of said main drive has accelerated to said predetermined speed, and means responsive to said sensing means for simultaneously disconnecting said auxiliary drive from said new core and for effecting engagement of said core with said main drive.

2. Continuous winding apparatus for web material comprising a reel for simultaneously supporting a winding roll and a new core, a main drive for selectively driving said roll and core, an indexing drive for said reel to advance said new core to a roll starting position, an auxiliary drive for driving said new core in said starting position at a predetermined rotational speed, means responsive to indexing of said new core to said starting position for causing driving engagement of said core with said auxiliary drive, additional means responsive to indexing of said core to said starting position for stopping said indexing drive, means operable only after operation of said additional responsive means for effecting cutting of said web and transfer of the cut leading end thereof to said core, means responsive to operation of said last named means for disconnecting said winding roll from said main drive, means responsive to operation of said disconnecting means for causing acceleration of said main drive to said predetermined rotational speed, means for sensing that the speed of said main drive has accelerated to said predetermined rotational speed, and means responsive to said sensing means for simultaneously disconnecting said auxiliary drive from said new core and for effecting engagement of said core with said main drive, and means responsive to the increasing thickness of the roll on said new core for again actuating said indexing drive to advance said core from said starting position to a winding position.

3. Continuous winding apparatus for web material comprising a reel for simultaneously supporting a winding roll and a new core, a main drive for selectively driving said roll and core, an indexing drive for said reel to advance said new core to a roll starting position, an auxiliary drive for driving said new core in said starting position at a predetermined rotational speed, means actuated by indexing of said new core to said starting position for causing driving engagement of said core with said auxiliary drive, a knife support mounted for movement between retracted and advanced positions, a knife carried by said knife support for cutting movement with respect thereto, means responsive to indexing of said core to said starting position for shifting said knife support to said advanced position, means responsive to movement of said knife support to said advanced position for preventing further operation of said indexing drive, means operable only in said advanced position of said knife support for causing operation of said knife to cut said web and transfer the cut leading end thereof to said new core, means responsive to said operation of said knife for disconnecting said winding roll from said main drive, means responsive to operation of said disconnecting means for causing acceleration of said main drive to said predetermined rotational speed, means for sensing that the speed of said main drive has accelerated to said predetermined rotational speed, and means responsive to said sensing means for simultaneously disconnecting said auxiliary drive from said new core and effecting engagement of said core with said main drive and for shifting said knife support to said retracted position to re-set said means for preventing operation of said indexing drive, and means responsive to the increasing thickness of the roll on said new core for again actuating said indexing drive to advance said core from said starting position to a winding position.

4. Continuous winding apparatus for web material comprising a reel for simultaneously supporting a winding roll and a new core, a main drive for selectively driving said roll and core, an indexing drive for said reel

5 to advance said new core to a roll starting position, an auxiliary drive for driving said new core in said starting position at a predetermined rotational speed, means actuated by indexing of said new core to said starting position for causing driving engagement of said core with said auxiliary drive, a pressure roll positioned to form a nip with said core at said starting position and to guide said web into said nip, a knife support mounted for movement between retracted and advanced positions, a knife carried by said knife support for cutting movement with respect thereto, means responsive to indexing of said core to said starting position for shifting said knife support to said advanced position, means responsive to movement of said knife support to said advanced position for preventing further operation of said indexing drive, means operable only in said advanced position of said knife support for causing operation of said knife to cut said web and transfer the cut leading end thereof to said nip for winding on said new core, means responsive to said operation of said knife for disconnecting said winding roll from said main drive, means responsive to operation of said disconnecting means for causing acceleration of said main drive to said predetermined rotational speed, means for sensing that the speed of said main drive has accelerated to said predetermined rotational speed, and means responsive to said sensing means for simultaneously disconnecting said auxiliary drive from said new core and effecting driving engagement of said core with said main drive and for shifting said knife support to said retracted position to re-set said means for preventing operation of said indexing drive, and means actuated by said pressure roll in response to movement thereof caused by the increasing thickness of the roll on said new core for causing said indexing drive to advance said core incrementally from said starting position to a winding position.

5. Auxiliary equipment for use in conjunction with winding apparatus for web material including a reel for simultaneously supporting a winding roll and a new core and provided with a main drive for selectively driving said roll and core and an indexing drive for advancing said new core to a roll starting position, comprising means forming a stand adapted to be mounted in predetermined relation with said reel, an auxiliary drive belt carried by said stand for engagement with said new core in said starting position, releasable means on said stand for tensioning said belt to drive said core at a predetermined rotational speed, a knife support mounted on said stand for movement between retracted and advanced positions, a knife carried by said knife support for cutting movement with respect thereto, means for shifting said knife support between retracted and advanced positions, means operable only in said advanced position of said support for causing operation of said knife in the direction to cut said web and transfer the cut leading end thereof to said new core in said starting position, and means responsive to said cutting operation of said knife for disconnecting said winding roll from said main drive, means responsive to operation of said disconnecting means for causing acceleration of said main drive to said predetermined rotational speed, means for sensing that the speed of said main drive has accelerated to said predetermined rotational speed, and means responsive to said sensing means for simultaneously releasing said drive belt from driving engagement with said core and for effecting driving engagement of said core with said main drive, and means for shifting said knife support to said retracted position substantially simultaneously with the operation of said last named means.

6. Auxiliary equipment for use in conjunction with winding apparatus for web material including a reel for simultaneously supporting a winding roll and a new core and provided with a main drive for selectively driving said roll and core and an indexing drive for advancing said new core to a roll starting position, comprising

means forming a stand adapted to be mounted in predetermined relation with said reel, an auxiliary drive belt carried by said stand for engagement with said new core in said starting position, releasable means on said stand for tensioning said belt to drive said core at a predetermined rotational speed, a pressure roll mounted on said stand in nip forming relation with said core at said starting position, a knife support mounted on said stand for movement between retracted and advanced positions, a knife carried by said knife support for cutting movement with respect thereto, means for shifting said knife support between retracted and advanced positions, means operable only in said advanced position of said support for causing operation of said knife in the direction to cut said web and transfer the cut leading end thereof to said nip for winding on said new core, means responsive to said cutting operation of said knife for disconnecting said winding roll from said main drive and causing acceleration of said main drive to said predetermined rotational speed, means for sensing that the speed of said main drive has accelerated to said predetermined rotational speed, and means responsive to said sensing means for simultaneously effecting driving engagement of said core with said main drive and for releasing said belt to disengage said core therefrom, and means actuated by said pressure roll in response to movement thereof caused by the increasing thickness of the roll winding on said core for causing said indexing drive to advance said core from said starting position.

7. Continuous winding apparatus for web material comprising a reel for simultaneously supporting a winding roll and a new core, a main drive for selectively driving said roll and core, an indexing drive for said reel to advance said new core to a roll starting position, an auxiliary drive for driving said new core in said starting position at a predetermined rotational speed, means responsive to indexing of said new core to said starting position and including a mechanism operated by fluid pressure for causing driving engagement of said core with said auxiliary drive, additional means responsive to indexing of said core to said starting position for stopping said indexing drive, means operable only after operation of said additional responsive means for effecting cutting of said web and transfer of the cut leading end thereof to said core, means responsive to operation of said last named means for disconnecting said winding roll from said main drive, means responsive to operation of said disconnecting means for causing acceleration of said main drive to said predetermined rotational speed, means operated by fluid pressure for effecting engagement of said core with said main drive, and means responsive to acceleration of said main drive to said predetermined speed for controlling the supply of fluid pressure to said fluid pressure operated mechanism and means simultaneously to effect simultaneously controlled engagement of said core with said main drive and disconnection of said auxiliary drive from said core.

8. Continuous winding apparatus for web material comprising a reel for simultaneously supporting a wind-

ing roll and a new core, a main drive for selectively driving said roll and core, an indexing drive for said reel to advance said new core to a roll starting position, an auxiliary drive for driving said new core in said starting position at a predetermined rotational speed, means responsive to indexing of said new core to said starting position for causing driving engagement of said core with said auxiliary drive, additional means responsive to indexing of said core to said starting position for stopping said indexing drive, means operable only after operation of said additional responsive means for effecting cutting of said web and transfer of the cut leading end thereof to said core, means responsive to operation of said last named means for disconnecting said winding roll from said main drive, means responsive to operation of said disconnecting means for causing acceleration of said main drive to said predetermined rotational speed, means for indicating that the speed of said main drive has accelerated to said predetermined speed, and means responsive to said indicating means for simultaneously effecting engagement of said new core with said main drive and disconnection of said auxiliary drive from said core.

9. Continuous winding apparatus for web material comprising a reel for simultaneously supporting a winding roll and a new core, a main drive for selectively driving said roll and core, an indexing drive for said reel to advance said new core to a roll starting position, an auxiliary drive for driving said new core in said starting position at a predetermined rotational speed, means responsive to indexing of said new core to said starting position and including a mechanism operated by fluid pressure for causing driving engagement of said core with said auxiliary drive, additional means responsive to indexing of said core to said starting position for stopping said indexing drive, means operable only after operation of said additional responsive means for effecting cutting of said web and transfer of the cut leading end thereof to said core, means responsive to operation of said last named means for disconnecting said winding roll from said main drive, means responsive to operation of said disconnecting means for causing acceleration of said main drive to said predetermined rotational speed, means for indicating that the speed of said main drive has accelerated to said predetermined speed, means operated by fluid pressure for effecting engagement of said core with said main drive, and means responsive to said indicating means for controlling the supply of fluid pressure to said fluid pressure operated mechanism and means simultaneously to effect simultaneously controlled engagement of said core with said main drive and disconnection of said auxiliary drive from said core.

UNITED STATES PATENT OFFICE
CERTIFICATE OF CORRECTION

Patent No. 2,943,806

July 5, 1960

Richard W. Phelps

It is hereby certified that error appears in the printed specification of the above numbered patent requiring correction and that the said Letters Patent should read as corrected below.

Column 2, line 4, for "from the" read -- form the --; column 6, line 45, for "manual" read -- manually --.

Signed and sealed this 27th day of December 1960.
